Nikolaus Gasenach

UNITED STATES PATENT OFFICE.

NIKOLAUS BASENACH, OF POTSDAM, GERMANY.

ANCHORING ARRANGEMENT FOR AIRSHIPS.

Application filed August 29, 1921. Serial No. 496,699.

(GRANTED UNDER THE PROVISIONS OF THE ACT OF MARCH 3, 1921, 41 STAT. L., 1313.)

To all whom it may concern:

Be it known that I, NIKOLAUS BASENACH, a citizen of the German Republic, residing at Potsdam, Germany, have invented new and useful Improvements in an Anchoring Arrangement for Airships (for which I have filed an application in Germany on August 22, 1913), of which the following is a specification.

10 My present invention relates to an anchoring arrangement for air-ships, and has for its object to provide improvements which ensure that thereby the air-ship is effectively protected against accidents caused by 15 violent winds. In consequence of my novel arrangement the anchoring action may be easily and readily carried out. My invention consists in providing an anchoring point beneath the forepart of the ship, as, 20 for instance, on the prow of the keel frame or beneath the front car, and pivotally joining this anchoring point directly to a suitable earth-anchor, whereby the ship is enabled to vertically oscillate and horizontally 25 revolve about this pivotal anchoring joint. As a suitable means for effecting this pivotal anchoring joint I may use an universal joint, a ball joint, a Cardan joint, of which one part is directly, or by means of 30 an intermediate member, secured to the anchoring point of the air-ship, while the second part of said joint is directly, or by means of an intermediate member, secured to said earth anchor. Instead of providing 35 said anchoring point at a downward projecting part of the ship prow, in order to allow the ship the necessary revolving and swinging play, I may dispose the said anchoring point directly beneath the fore part 40 of the carrying body of the ship and raise the earth anchor to such a height that the necessary revolving and swinging play is secured. Or I may provide the carrying body of the air ship with a downward directed 45 rigid structure the end of which is then pivotally connected to the earth anchor which need not project above the ground. It is one essential feature of my present invention that the air ship is enabled to readily 50 revolve and oscillate about the anchoring point and that this point is disposed beneath the front part of the air ship. Another essential feature of my present invention is that the anchoring connection is secured by

means of an universal joint which securely 55 prevents any longitudinal movements within the axis of the ship body although it allows the ship the necessary revolving and swinging play. By suitably adjusting the horizontal rudder of the air ship any contact of the rear of the ship with the ground 60 can be easily prevented.

To carry my invention into effect I do not require high stationary columns which are expensive to erect and to maintain, and 65 I do not require reenforced end constructions of the carrying body of the ship, since, with my invention the one part of the pivotal joint may be secured to some transversal frame work parts of the carrying 70 body, which, parts for that purpose, may be somewhat stronger constructed than the others if considered necessary.

In order to render my invention quite clear I have illustrated some embodiments 75 of the same in the accompanying drawings, by way of example.

Fig. 1 is a diagrammatic elevation of an air-ship anchored directly to the ground with the front end of its stiffening frame. 80

Fig. 2 illustrates the application of a raised and earth-anchored structure.

In Fig. 3 the front car is provided with one part of the pivotal joint and in

Fig. 4 this part of the pivotal joint is 85 secured directly beneath the prow of the carrying body of the ship, this arrangement necessitating the application of a raised and earth-anchored structure.

In Fig. 5 a downward projecting structure is fixedly secured to the prow of the ship body. And in

Fig. 6 the anchoring arrangement illustrated in Fig. 4 is shown on an enlarged scale. 95

In the examples shown in the drawings the air ship is designated *a* and is provided with one part *b* (compare Fig. 6) of an universal joint, the supplementary part *c* being either secured directly to the earth anchor or to a raised structure *d*. The part *b* may be fixed to the front end of the stiffening frame work *g* as shown in Fig. 1, or to the front end of the keel frame as in Fig. 2. In this case, the supplementary part *c* of the universal joint is fixed at 100 the termination of a raised structure *d* secured to the ground by means of earth 105

anchors *e*, *e* (compare Fig. 6). The part *b* of the universal joint may be secured to the front end of the front car as in Fig. 3 and directly connected to the 5 earth anchors *e*, *e* by means of the supplementary part *c* of the universal joint. If the part *b* is fixed directly to the lower surface of the body of the air ship, the raised structure *d* must then be of such a 10 height that the front car is prevented from touching the ground (see Fig. 4). In this case there must be a very reliable connection between the car and the main body of the ship. I may obtain the same effect by 15 providing a rigidly secured structure *d*¹ beneath the fore part of the main body of the ship, as shown in Fig. 5, which eliminates the necessity of providing such structures on the ground on which only ordinary 20 earth-anchors are required.

By suitably adjusting the horizontal rudder *f* the air ship can readily be maintained in the inclined position shown in the drawings.

25 I am aware that other modifications may be made within the scope of my invention.

What I claim as my invention and desire to secure by Letters Patent of the United States, is:—

1. An anchoring arrangement for air-ships, comprising, in combination, an anchoring point beneath the lowest part at the front of the ship and forming a rigid projection of said part, an anchoring device constructed and secured so as to form 30 a rigid projection of the anchoring place, and a pivotal connection between said anchoring point of said ship part and said anchoring device, whereby said ship is allowed a revolving and oscillating movement about the axis of said pivotal connection.

2. An anchoring arrangement for air-ships, comprising, in combination, a downward projecting structure at the front part 45 of the ship, said structure being rigidly secured to said ship and of such a length that its termination forms the lowest point of the front part of the ship, a part of an universal joint rigidly connected to the lower termination of said structure, an anchoring device constructed and secured so as to form a rigid anchor at the anchoring place, and a supplementary part of the universal joint rigidly connected to said rigid 50 anchor at the anchoring place.

NIKOLAUS BASENACH.
